UNITED STATES PATENT OFFICE.

GEORGE POLLOCK AND WILLIAM E. WERD, OF DEER LODGE, MONTANA, ASSIGNORS OF ONE-
THIRD TO SIDNEY C. HOUK, OF DEER LODGE, MONTANA.

CLAMP-INSULATOR.

No. 869,018.

Specification of Letters Patent.

Patented Oct. 22, 1907.

Application filed May 9, 1907. Serial No. 372,804.

To all whom it may concern:

Be it known that we, GEORGE POLLOCK and WILLIAM E. WERD, both citizens of the United States, and residents of Deer Lodge, in the county of Powell and State of Montana, have invented a new and Improved Clamp-Insulator, of which the following is a full, clear, and exact description.

Our invention relates to insulators, our more particular object being to provide a type of insulator made in halves and adapted to exert leverage upon a wire, so as to grip it tightly in position as well as to insulate it thoroughly from surrounding parts, and also to protect it within certain limits from the effects of moisture.

Our insulator may be made in various forms, some of which are herein shown.

Reference is to be had to the accompanying drawings forming a part of this specification, in which similar characters of reference indicate corresponding parts in all the figures.

Figure 1 is a front elevation of a post showing various ways whereby our insulator may be mounted thereupon so as to support wires; Fig. 2 is an enlarged elevation, partly in section, showing two of our insulators secured in the same plate; Fig. 3 is an elevation, partly in section, of another form of the clamp used as an insulator pin, and showing the arrangement of the bearings for gripping the wire and the cap for protecting a portion of the wire from the effects of moisture; Fig. 4 is a plan view of a plate used for holding three of our improved insulators; and Fig. 5 is a fragmentary vertical section upon the line 5-5 of Fig. 4, looking in the direction of the arrow, and showing the obliquely disposed walls for retaining the supporting block.

A post 6 is provided with plates 7, 8 secured thereto by bolts 9, 10. Removably fitted within the plate 7 is a block 11 which we denominate as a supporting block. The shape of this block can be seen from Fig. 2. In the plates 8 the supporting blocks are shown at 12 and have a conformity slightly differing from that of the supporting block 11. Clamping members 13 are arranged in pairs, each pair constituting in effect the body of our insulator pin. Fitted within these clamping members 13 are bearing boxes 14 of semi-cylindrical form, upon which the clamping members 13 are adapted to exert pressure. The clamping members 13 differ slightly in design from the clamping members 18. A wire is shown at 16 and is gripped tightly between the two semi-cylindrical bearing boxes 14. A screw cap 17 is provided with a hood 18 and threaded internally as shown in Fig. 2. In all instances the upper ends of the clamping members are each threaded so as to be fitted with the screw cap.

In the form shown in Fig. 2 the plate 19 is adapted to accommodate two insulators. For this purpose it is provided with raised walls 20 inclined toward each

other and is secured in position by aid of bolts 21. The clamping members 22 are paired together as above explained and are fitted with semi-cylindrical bearing boxes 23 also paired, and arranged to grip the wire 16. The semi-cylindrical bearing boxes 23 are provided with flanges 23^a for the purpose of preventing removal of the bearing boxes.

The clamping members 22 are provided with ends 24 turned outwardly or slightly hooked, as indicated in Fig. 2. These clamping members are further provided with shoulders 25 for affording a slight space or crack 26 intermediate the clamping members. They are threaded at 27 for the purpose of receiving upon their outer ends the screw cap 17. The general construction of all the details will be apparent by reference to Fig. 2.

In assembling, one of the clamping members 22 is inserted within the block 11, the other is next partially inserted therein, the bearing boxes 23 are placed in position upon opposite sides of the wire 16, and finally the clamping members are brought as nearly together as possible so that the bearing boxes grip the wire. The screw cap 17 is next secured in position, so as to increase the pressure upon the wire and thus prevent any relative movement as between the wire and the clamping members.

In the form shown in Fig. 3 the plate 28 is provided with bolts 29; whereby it is secured in position, and is further provided with a projecting portion 30 having an aperture 31 therein. Clamping members 33 are made in pairs and are provided with outwardly hooked ends 32 which fit into the aperture 31. The clamping members 33 are provided at their upper end with a thread 34, upon which is fitted the cap 17 provided with a hood 18, substantially as above explained with reference to the other figures. Semi-cylindrical bearing boxes 35 are provided with rotund portions 36, the rotundity of the latter being concentric with that of the wire 16. The purpose of the rotund portions 36 is to prevent any possibility of the bearing boxes slipping relatively to the clamping members 33.

In Fig. 4 is shown a plate 37 provided with screw holes 38 and with inclined walls 39 encompassing apertures 40. The purpose of this plate 37 is to hold three insulators of any of the kinds above described.

When the screw cap 17 is in position, the hood 18 projects outwardly a little distance, and tends to serve as a shield for preventing the entrance of moisture into the body of the insulator at a point where it might otherwise cause leakage of current from the wire.

It will be noted that owing to the abrupt taper of the threaded portions 27, 34 one size of insulator may be used for different size wires. The clamps, bases and caps may be made of any suitable metal or of porcelain or wood.

We do not limit ourselves to the construction shown as reasonable variations may be made therefrom without departing from the spirit of our invention.

Having thus described our invention, we claim as new and desire to secure by Letters Patent:

- 5 1. The combination of a block provided with an aperture, a pair of clamping members provided with hooked ends extending into said aperture, bearing members mounted upon said clamping members and adapted to engage a 10 wire, and means for holding together said clamping members so as to cause the same to grip said wire.
- 15 2. The combination of a supporting block provided with an aperture, a pair of clamping members mated together and fitted into said aperture, bearing members mounted upon said clamping members and adapted to engage a wire, and a member engaging both of said clamping members for holding the same together.
- 20 3. The combination of a supporting block, clamping members made in pairs and provided with shoulders for spacing said members slightly apart, and being further

provided with means for engaging a wire, and a cap engaging said clamping members for the purpose of causing the same to grip said wire.

4. The combination of a supporting block, provided with an aperture, clamping members made in pairs and provided with hooked ends extending into said aperture, means mounted upon said clamping members for engaging a wire, and a cap encircling said members for increasing the pressure upon said wire.

5. The combination of a pair of clamping members disposed upon opposite sides of a wire to be supported, and a cap engaging said clamping members and provided with a hood for protecting the same from moisture.

In testimony whereof we have signed our names to this specification in the presence of two subscribing witnesses. 35

GEORGE POLLOCK,
WILLIAM E. WERD.
